US0D1044894S

(12) **United States Design Patent** (10) Patent No.: **US D1,044,894 S**
(45) Date of Patent: ** Oct. 1, 2024

(54) **BUTTON DRILL BIT**

(71) Applicant: **Zhejiang Pulanka Rock Tools Co., Ltd.**, Taizhou (CN)

(72) Inventor: **Guohua Shen**, Taizhou (CN)

(73) Assignee: **Zhejiang Pulanka Rock Tools Co., Ltd.**, Taizhou (CN)

(**) Term: **15 Years**

(21) Appl. No.: **29/849,008**

(22) Filed: **Aug. 8, 2022**

(30) **Foreign Application Priority Data**

Jul. 9, 2022 (CN) 202230434377.3

Robit, Button Bits, not date avail, [searched Feb. 13, 2024], <https://www.robbitgroup.com/?productgroup=button-bits> (Year: 2024).*

Primary Examiner — Mary Shannon Malley
Assistant Examiner — Olivia H Aldin

(57) **CLAIM**

The ornamental design for a button drill bit, as shown and described.

DESCRIPTION

FIG. 1 is a perspective view of a button drill bit showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in the figures illustrate the portions of the button drill bit that form no part of the claimed design.

1 Claim, 7 Drawing Sheets
